UNITED STATES PATENT OFFICE.

JAMES E. BRUNDAGE, OF WILLIAMSBURG, BROOKLYN, ASSIGNOR OF ONE-HALF HIS RIGHT TO EUGENE F. BRUNDAGE, OF HARLEM, NEW YORK.

IMPROVEMENT IN VISSES.

Specification forming part of Letters Patent No. 177,090, dated May 9, 1876; application filed September 15, 1875.

To all whom it may concern:

Be it known that I, JAMES E. BRUNDAGE, of Williamsburg, in the city of Brooklyn, county of Kings and State of New York, have invented an Improved Vise; and I do hereby declare that the following is a full, clear, and exact description of the same, reference being had to the accompanying drawing, making part of this specification.

My invention relates to a novel mode of providing for the admission of different thicknesses of work between the jaws of a vise by rapidly opening and closing the jaws independently of the screw.

The invention consists in the combination of a divided nut, and a device of novel construction for operating the same, whereby the nut and screw may be readily disengaged to allow the movable jaw to be rapidly moved toward or away from the fixed jaw, and again thrown into engagement to provide for the nice adjustment of the jaws.

In the accompanying drawing, Figure 1 is a side view of a vise constructed according to my invention. Fig. 2 is a longitudinal vertical section. Fig. 3 is an end view, partly in section. Fig. 4 is a detail sectional view.

A represents the fixed jaw, and B the movable jaw, the bar *b* of which is hollow and slides in the fixed jaw A, in the usual manner. In the fixed jaw is an upright frame, D, which carries a nut composed of two halves, C¹ C². The upper half, C², is fixed, and may consist simply of a thread cut in the upper part of the frame D. The lower half, C¹, is arranged to slide vertically in the lower part of the frame. Under the lower half is a wedge-shaped piece, F, sliding nearly horizontally in the frame D in a groove, *d*, the bottom of

which is an incline plane. The rear or larger end of the wedge F is connected by an arm, *l*, with a rock-shaft, I, provided with a lever or handle, *h*, at one end, outside of the jaw A. When the lever *h* is elevated the wedge F is drawn outward, so as to allow the lower half of the nut to fall out of contact with the screw G, whereupon the movable jaw B may be rapidly moved by hand, so as to slide inward or outward, either toward or from the fixed jaw, the bar *b* sliding in its seat in the fixed jaw. When the lever *h* is depressed the wedge F is driven inward and upward on the inclined plane, so as to raise the lower half of the nut and throw it into engagement with the thread on the screw G, and thus provide for the nice adjustment of the jaws by means of the screw, and also prevent the moving of the jaw B, except by turning the screw in the usual manner. A catch, *m*, is provided on the jaw A for engagement with the lever *h*, to hold it in place when it is depressed to tighten the nut, as shown in Fig. 3. Instead of a straight sliding wedge, as shown, the tightening device may consist of a cam or eccentric attached to or connected with the rock-shaft in any suitable manner, so as to produce a result similar to that of the wedge.

What I claim as new, and desire to secure by Letters Patent, is—

The divided nut, consisting of a movable half, C¹, and fixed half, C², the wedge F, and the rock-shaft I, in combination with the screw and jaws of a vise, substantially as and for the purpose herein described.

JAMES E. BRUNDAGE.
